METHOD OF AND APPARATUS FOR OPENING
AMPOULES

Ralph E. Maxwell, Modesto, Calif.

Application January 31, 1939, Serial No. 253,856

5 Claims. (Cl. 49—48)

This invention relates to medical equipment and more particularly refers to improvements in devices for cutting glass ampoules of the type widely used as containers for medical preparations.

An ampoule is a cylindrical glass container having a sealed elongated neck which is broken off when the preparation within the ampoule is to be transferred to a syringe by means of a 10 hypodermic needle inserted within the resulting opening.

This type of container is, of course, widely used for medical preparations because of the absolute protection against oxidation and deterioration thereby afforded to its contents under strictly sterile conditions free from contact with air. An ampoule will also insure accuracy of dosage and supply the physician with a very 20 definite amount of the particular drug therein contained.

However, the necessity of breaking off the tip of the neck of the ampoule, in order to remove the liquid contents, is seriously objectionable on several grounds as it gives rise to difficulties and 25 occurrences which interfere with the work of the physician and which frequently present dangerous possibilities.

Ordinarily the ampoule is opened by producing an annular groove around the neck of the 30 ampoule by means of an ordinary triangular or knife edged file and then snapping off by hand the portion of the neck beyond the point weakened by the groove. The glass from which these ampoules are made varies materially in hardness, strength and thickness. Some ampoules are so thin-walled as to make filing very difficult. Frequently, the pressure exerted by the 35 file against the neck of the ampoule will cause it to shatter into numerous small glass fragments which may penetrate the fingers or fly into the operator's eyes. Finger lacerations are frequent and are a serious menace to the surgeon, scientist or nurse who so often come in contact with serious types of infectious germs.

Frequently when the neck of the ampoule is shattered or when the edge of the file bites too 40 deep, the contents of the ampoule comes in contact with the file. The file is never sterile; therefore, the contents of the ampoule may become contaminated with organisms which may prove a fatal issue. Usually the same file is used for filing all kinds of ampoules, containing 45 all types of chemicals and drugs and this practice may result in the contamination of one preparation by another, giving occurrence to

chemical reactions radically altering the properties of a drug.

Let us suppose, for instance, that a file be used in opening an ampoule of sodium iodide solution. The file may come in contact with this solution and a small quantity of it may stick and dry upon the surface of the file. If an ampoule containing Salvarsan is opened later with the same file and a small amount of sodium iodide sticking to the surface of the file should 5 find its way into the Salvarsan ampoule, the Salvarsan would be dangerously affected because only an infinitesimal amount of sodium iodide is sufficient to decompose the complex arsenical formula which may thereby become 10 highly toxic and poisonous. I believe this admixture of chemicals occurs much more frequently than would be supposed and supplies a plausible explanation for many unexplained 15 toxic reactions accompanying intravenous 20 therapy where the drug is injected directly into the blood stream.

The main object of the present invention is to provide a novel and improved method of producing an annular groove about a tubular glass 25 body, such as the neck of an ampoule, whereby an even indentation may be produced by the application of only a light and uniform pressure against the ampoule, without danger of shattering the glass and without danger of the cutting 30 implement breaking through the glass.

Another object is to provide a novel and improved device for opening ampoules, making it possible to cut an accurate annular groove around the neck of the ampoule, producing a 35 clean-cut breakage point, which when the tip is broken off leaves a smooth even edged surface in the edge of the remaining ampoule neck with no jagged or sharp points.

A further object is to provide a novel and improved device of the character specified, comprising an operating member having a cutting or abrasive edge and means for supporting an ampoule, adjustable with respect to said member, in order to enable the device to handle 40 ampoules of different diameters and lengths.

A still further object is to provide a device of the character specified, built in very compact form, and adapted to be easily secured onto a 45 table or wall.

Other objects and advantages of the present invention will more fully appear as the description proceeds and will be set forth and claimed 50 in the appended claims.

My invention is illustrated by way of example in the accompanying drawings, in which:

Fig. 1 is a front view in elevation of a manually operated device, embodying my invention;

Fig. 2 is a vertical cross section of the same;

Fig. 3 is a rear view in elevation thereof;

Fig. 4 is a fragmentary vertical section in an enlarged scale through line 4-4 of Fig. 2; and

Fig. 5 is a vertical longitudinal section of a device, embodying my invention, in an alternative form.

The method forming one of the objects of my invention essentially consists in cutting an annular groove at a desired point along the neck of an ampoule by lightly pressing the ampoule against a moving implement having a cutting or abrasive edge, while supporting the body of the ampoule in a manner permitting of its being rotated by hand while the cutting operation takes place. The ampoule is preferably supported only at or near the rear end, so that its front or neck extension will rest upon the abrasive edge by virtue of its own weight, the pressure applied against the ampoule by the finger in order to rotate the ampoule being sufficient to cause the abrasive edge to bite into the neck of the ampoule without cutting through it.

In order to cut the groove at the exact point desired, the bottom of the ampoule is made to rest against an adjustable abutment which may form an integral part of the rear end support, if desired.

The cutting implement is preferably in the form of a rapidly rotating thin disk of abrasive material, of the type widely used, for instance, in dental surgery. After a groove of the proper depth has been cut around the neck of the ampoule, the tip end thereof can be inserted through an opening of suitable size, and force may be applied against the body of the ampoule tending to deflect it from the direction of the opening, thereby causing a clean-cut break to occur at the grooved point.

Since the ampoule is filled with liquid, the opening through which the tip end of its neck is inserted should be directed upwardly, so that when the tip of the neck is snapped off the body of the ampoule, no part of the liquid contents will be spilled.

The reason why it is preferable to allow the neck of the ampoule to lightly rest against the cutting edge of the disk or other implement is that the neck of the ampoule is generally not exactly circular in shape or exactly coaxial with the body of the ampoule, so that if the ampoule were so supported that a definite distance were left between its axis and the edge of the cutting implement an uneven cutting might result; the cutting edge might not even touch the surface of the neck of the ampoule at certain points and at certain other points it might cut too deeply into the glass, enough to cut right through it, an occurrence which must be strictly prevented in order to prevent contamination of the drug.

When the ampoule is supported only at the rear end its front end can easily move up and down so as to constantly maintain the surface of the neck in contact with the cutting edge in spite of the irregularity or eccentricity of said surface.

My invention can be embodied in a relatively simple and compact device, a form of which, adapted for manual operation, is shown in Figs. 75 1 to 4.

The device therein illustrated comprises a hollow frame 10, forming a chamber 11 closed at the rear by means of a closure member 12, said frame having a downward and inward gooseneck extension 13, forming with the lower surface 14 of the frame a recess 15, adapted to receive the edge of a table top, shown in dot and dash lines at 16.

The lower end of gooseneck extension 13 is provided with a clamping screw 17, which makes it possible to firmly clamp the device in position in a well known manner.

Closure member 12 is equipped with a rearwardly extending bracket 18, having a substantially horizontal top section 19 along which is slidably mounted a V-shaped member 20, adapted to provide a support for the rear end of the ampoule, such as shown in dot and dash lines at 21. Said member 20 is preferably made integral with a wall 22, vertically extending from the rear thereof, providing an abutment for the bottom of the ampoule.

The forward end of the upper part of the bracket forms with the rear surface of closure member 12 a pocket or depression 23, providing a clearance space within which is housed an abrasive disk 24, carried by a shaft 25.

Said shaft is rotatably supported by the front wall of frame 10 and closure member 12, which, as stated, forms the rear wall of chamber 11. The shaft extends across said chamber 11 and projects at the rear beyond closure member 12, the rear end of said shaft being provided with a clamping nut 26, retaining the abrasive disk in position.

The part of said shaft extending within chamber 11 carries, or is formed integral with, a pinion portion 27, and also carries a flywheel 28.

Pinion 27 is driven by means of a driving gearwheel 29, meshing therewith, said gearwheel having a diameter considerably greater than that of pinion 27. Gearwheel 29 is carried by a driving shaft 30, rotatably mounted across chamber 11, the front end of said shaft 30 projecting through the front wall of frame 10 and carrying or being formed integral with a crank handle 31, adapted for manual operation. It is obvious that when shaft 30 is rotated, its movement will be transmitted to the abrasive disk at a much greater speed, such as will make it possible for said disk to operate under the best conditions.

As stated, the supporting member 20 is adjustable along the bracket to and from the abrasive disk, according to the length of the ampoule to be cut. For instance, at 32, I show in dot and dash lines, an ampoule which is much shorter than ampoule 21 and which calls for a forward displacement of supporting member 20 from the position shown in full lines in Fig. 2 to the position shown in dot and dash lines at 20'.

Ampoules do not vary only in length but also in diameter, as shown in said Fig. 2, where ampoule 32 has a diameter much smaller than that of ampoule 21. In all cases the neck of the ampoule should rest upon the abrasive disk, as shown, while the ampoule lies in a substantially horizontal position. This calls for a vertical adjustment of the ampoule support, sufficient to counterbalance the difference in diameter between the smallest and largest ampoule that the device will be called upon to handle.

A vertical adjustment of the ampoule support is obtained by providing the front end of bracket 18 with a vertically elongated opening 33, through which is inserted the stem portion of a

clamping screw 34, permitting vertical adjustment of the bracket within the limit permitted by the length of said opening 33.

The central line of the bracket coincides with the plane of the axis of shaft 25 and its proper alignment in all positions is assured by mounting said bracket between two guiding ribs 35, 36, projecting from the rear surface of closure member 12, as Fig. 3 clearly shows. A groove 10 can be cut at the desired point around the neck 37 of the ampoule by lightly pressing the body of the ampoule downwardly with the tip of the finger, at the same time causing said ampoule to rotate about its own axis. The finger will be 15 applied to the body of the ampoule at the rear directly above the supporting member 20, so that the front end of the ampoule will be urged against the cutting edge of the disk with a force which is very light and easily controllable, 20 just sufficient to cause the abrasive disk to gradually cut into the glass in a uniform manner without breaking through it.

The rotation of the disk naturally tends to laterally displace the neck of the ampoule contacting therewith, therefore, it is necessary to restrain the ampoule against such movement by maintaining it with its axis in a common plane with the axis of shaft 25. To this end, I provide the part of closure member 12 immediately 25 above shaft 25 with two laterally spaced walls 38, 39, defining a central clearance space 40, within which the tip end of the ampoule projects when the ampoule is in the proper groove cutting position, as shown in Fig. 2.

In view of the fact that not only the bodies of the ampoules but also their neck portions are of different diameters, I prefer to make the clearance space 40 between walls 38, 39, adjustable to suit ampoule necks of various diameters, 30 and to this end, I make each of said walls 38, 39, integral with a base flange, such as shown at 41, 42, in Fig. 3, provided with a horizontal slot 43, through which is inserted the stem of a clamping screw 44, cooperating with said slot in 35 permitting lateral adjustment of said walls 38, 39.

After the groove has been cut in the neck of the ampoule to the proper depth it is desirable to quickly stop the movement of the abrasive 40 disk and to this end I provide the device with a push button brake, such as shown at 45, adapted to press against the surface of flywheel 28, said brake being normally held out of contact with said flywheel by a spring 46.

After the groove has been cut the tip of the ampoule can be snapped off by hand, but preferably I provide the rear end of bracket 18 with a series of openings 47, of various diameters, adapted to receive and retain the tip end of an 55 ampoule, while the ampoule is deflected downwardly to cause the tip end of its neck to snap off, as shown in dot and dash lines at 21' in Fig. 2.

An abrasive disk made of any suitable abrasive material will last a very long time, and by 60 providing the frame with an enclosure, such as shown at 48, normally sealed by a cover 49, I make it possible to store within the device enough abrasive wheels for replacement purposes to insure several years of uninterrupted service.

Although the device is shown as being provided with means for clamping it onto a table top, it is obvious that by suitably modifying the shape of the frame it is possible to make the device adapted to be mounted against a wall 70 in any well known manner.

The supporting member 20 is preferably mounted in a manner enabling it to be quickly shifted along bracket member 18 and to be automatically retained against displacement from any position in which it may be set. A simple 5 arrangement is shown in Fig. 4, where it is seen that the supporting member 20 is frictionally held in position along member 18 of bracket 18 by a deformable spring 50, urging said member 20 downwardly against the surface 10 of member 18 while permitting sliding movement of said member 20 along member 18.

If desired, the mechanism can be electrically instead of manually operated. For instance, in Fig. 5 I show a similar device in which the shaft 51, carrying the abrasive disk 52, and formed with a pinion section 53, is driven by the pinion 54 of an electric motor 55, through the intermediary of an idler wheel 56. The electric motor can be connected to any wall socket by 20 means of a plug 57, attached to the end of a flexible connection 58 in the usual manner.

The device shown in Fig. 5 exemplifies the previously mentioned possibility of attaching it to a wall the frame 59 of the device being formed, 25 as shown, with a vertical base flange 60, provided with screw holes 61.

If desired, the electrically operated device shown in Fig. 5 also can be equipped with braking means of any suitable character. For instance, the shaft of the electric motor can be equipped with a drum or pulley 62, against which can be forced the brake shoe portion 63 of a lever 64, pivotally mounted at 65 and formed with a compressible extension 66.

My invention possesses a number of advantages which make it an important addition to the equipment of a physician's office. The device makes it possible to quickly open ampoules of all sizes, saving considerable time. This is 40 important not only because the machine can accomplish in a few seconds a result which generally requires a few minutes by present methods, but also because at times the saving of minutes may be a matter of life or death. The device 45 provides a clean-cut line of breakage and eliminates the possibility of crushing the ampoule and scattering flying glass fragments. It eliminates the loss of costly ampoules due to frequent breakage while opening. Some ampoules 50 cost as much as five dollars each.

In addition, the use of the device insures the contents of the ampoule against contamination by infectious germs and also against the possibility of harmful chemical reactions taking 55 place.

The device is professional in appearance and enhances the prestige of the physician and of his office equipment.

It is also possible to make the device so that it can be used for not only cutting glass ampoules but also glass tubing. For instance, in Fig. 5 the top of the frame 59 is shown at a level lower than that of the upper part of the abrasive disk, so 60 that there are no obstructions in the path of a length of tubing projecting beyond the abrasive disk to a material extent.

Many constructional details of my device may vary from those shown without departing from 70 the inventive idea. The drawings should, therefore, be understood as being intended for illustrative purposes only and not in a limiting sense.

I, accordingly, reserve the right to carry my invention into practice in all those ways and man- 75

ners which may enter, fairly, into the scope of the appended claims.

I claim:

5. 1. The method of cutting an annular groove about the neck of an ampoule serving as a container for a chemical preparation for the purpose of opening said ampoule, which consists in placing the ampoule in a horizontal position while supporting the rear end only of the body of the 10 ampoule, resting the neck portion against a rotating continuous abrasive edge, confining the ampoule against bodily movement in a direction laterally thereof while permitting movement in a vertical direction, exerting a light pressure on 15 the supported end of the ampoule body and simultaneously rotating said ampoule about its own axis.
2. The method of cutting an annular groove about the neck of an ampoule serving as a container for a chemical preparation for the purpose of opening said ampoule, which consists in placing the ampoule in a horizontal position while supporting the rear end only of the body of the 20 ampoule, resting the neck portion against a rotating continuous abrasive edge, confining the ampoule against bodily movement in a direction laterally thereof while permitting movement in a vertical direction, exerting a light pressure on the supported end of the ampoule body while rotating 25 said ampoule about its own axis, at the same time maintaining the ampoule with its axis in a plane substantially at right angles to the plane of said edge.
3. An ampoule cutting device comprising a 30 frame, a disk having an abrasive edge revolvably mounted on said frame, a bracket carried by said frame adjustable to and from the axis of said disk, an ampoule body support adjustable upon said bracket to and from the plane of said disk 35 in a direction at right angles to said plane and so positionable with relation to said disk that an ampoule with the rear end of its body portion placed on said support would have its neck extended in contact with said disk and projecting

beyond said disk, said support being so constructed as to prevent substantial lateral movement in a direction tangential to the edge of the disk of an ampoule mounted thereon and permitting movement of said ampoule in a direction to and from 5 said disk.

4. An ampoule cutting device comprising a frame, a disk having an abrasive edge revolvably mounted on said frame, a bracket carried by said frame adjustable to and from the axis of said disk, an ampoule body support adjustable upon said bracket to and from the plane of said disk 10 in a direction at right angles to said plane and so positionable with relation to said disk that an ampoule with the rear end of its body portion 15 placed on said support would have its neck extended in contact with said disk and projecting beyond said disk, said support being so constructed as to prevent substantial lateral movement in a direction tangential to the edge of the disk of an 20 ampoule mounted thereon and permitting movement of said ampoule in a direction to and from said disk, and additional means for limiting the lateral movement of the tip of said ampoule, said means positioned adjacent the side of the disk 25 opposite to that of the support.

5. An ampoule cutting device comprising a frame, a disk having an abrasive edge revolvably mounted on said frame, a bracket carried by said frame adjustable to and from the axis of said disk, a V-shaped ampoule body support adjustable upon said bracket to and from the plane of said disk 30 in a direction at right angles to said plane and so positionable with relation to said disk that an ampoule with the rear end of its 35 body portion placed on said support would have its neck extended in contact with said disk and projecting beyond said disk, said V-shaped support preventing substantial lateral movement of an ampoule mounted thereon in a direction tangential to the edge of the disk and permitting movement of said ampoule in a direction to and from said disk. 40

RALPH E. MAXWELL.
